United States Patent Office.

WILLIAM MURRAY, OF ALEXANDRIA, VIRGINIA.

Letters Patent No. 99,463, dated February 1, 1870.

CORN-HARVESTER.

The Schedule referred to in these Letters Patent and making part of the same.

To all whom it may concern:

Be it known that I, WILLIAM MURRAY, of Alexandria, in the county of Alexandria, and State of Virginia, have invented a new and valuable Improvement in Corn-Stalk Cutter; and I do hereby declare that the following is a full, clear, and exact description of the construction and operation of the same, reference being had to the annexed drawings, making a part of this specification, and to the letters and figures of reference marked thereon.

Figure 1, of the drawings, is a top view.

Figure 2 is a longitudinal sectional view.

My invention has relation to means for cutting corn-stalks; and

It consists mainly in the construction and novel arrangement of devices intended to serve an efficient purpose in cutting standing hills of corn-stalks, and passing them in suitable bundles to the ground ready for binding.

To this end I construct a carriage in two sections, to be moved upon three wheels, which sections, for descriptive purposes, I have marked respectively A and B on the drawings.

Section A has two large wheels *a a*, firmly attached to the axle, and rotating therewith.

The frame C rests upon the axle a little in the rear of the longitudinal centre, and its front end is in part supported by the caster D.

I attach a pinion, *e*, to the axle, which gears with the pinion *f* on the longitudinal shaft next mentioned.

F is a shaft resting and revolving on bearings in the frame C. The pinion *f* is attached to its rear end, and the crank-wheel *g* to its front, in the manner shown on fig. 1.

The letter *h* represents the driver's seat, and *i*, the foot-rest, both arranged on section A. The front end of frame C is constructed, so as to form the hounds of the carriage in which the neap is arranged.

I attach a plate, *H*, under the hounds, as shown, which serves as an aid in supporting the front end of the frame, by bringing a portion of the weight thereof upon the neap.

The section B is attached to section A, by means of the cross-beams *G* and *H*, in the manner shown on fig. 1. It consists mainly of the platform K, elevated sides L, axle M, with fixed wheel N, together with the cutting and unloading-apparatus next described.

O represents the cutting-bar connected with the crank *g*, by the rod *n*, and by means of which rod and crank, it is forced to vibrate back and forth automatically.

The knives upon this bar are marked *r* on the drawings. They are formed with enlarged diamond-shaped points, and curved cutting-edges, as shown.

The letters *s* represent grooved or slotted fingers, in which the knives vibrate, and against the curved sides of which the corn-stalks are cut.

P represents my gathering-reel. It consists of a vertical-rotating standard, with curved arms, as shown.

The letter *u* represents a drum attached to the lower end of this reel.

I form a similar drum upon the axle M, and a band or belt, *v*, is passed over both to operate said reel.

At the rear end of the platform K, I affix the rolling-bar *m*, to which I attach the arms *p* and *w*.

Y is a rod, extending from arm *w* to the rake *a'*, to which it is hinged.

A rod, *c'*, extends from arm *p* to the lever R, which lever is pivoted to the side of section B in the manner shown.

To operate my device, the machine is drawn forward, the team travelling to the left of a standing row of corn, and bringing the front end of section B immediately in the rear thereof.

The movement of the wheels *a a*, and their connections, causes the cutting-bar to vibrate to the right and left, and cut the stalks. The wheel of section B and its connections rotate the reel, and thereby press the stalks firmly against the fingers for cutting, and when cut, carries the stalks rearward upon the platform K. When a quantity of stalks, sufficient for a bundle, has thus been cut and conveyed to the platform, the operator draws the top of lever R rearward, and thereby by forces such bundle from the platform to the ground.

What I claim as my invention, and desire to secure by Letters Patent, is—

1. The roller *m*, arms *p* and *w*, rods *Y* and *c'*, rake *a'*, and lever R, when combined with the platform K, and arranged to operate as specified.

2. The arrangement herein shown, of the shaft *F*, pinions *e* and *f*, crank *g*, rod *n*, cutting-bar *O*, knives *r*, and reel *P*, with its curved arms as described, when the same are combined with the platform K, and discharging-apparatus specified.

In testimony that I claim the above, I have hereunto subscribed my name, in the presence of two witnesses.

WILLIAM + MURRAY.
mark.
